UNITED STATES PATENT OFFICE.

DANIEL W. SHIEK, OF INDIANAPOLIS, INDIANA, ASSIGNOR TO WALTER L. MILLIKEN,
OF BARNSTABLE, MASSACHUSETTS.

COMPUTING-MACHINE OR THE LIKE.

1,136,725.

Specification of Letters Patent. Patented Apr. 20, 1915.

Application filed February 19, 1908. Serial No. 478,888.

To all whom it may concern:

Be it known that I, DANIEL W. SHIEK, a citizen of the United States, residing at Indianapolis, in the county of Marion and State of Indiana, have invented certain new and useful Improvements in Computing-Machines or the like, of which the following is a description.

My invention belongs to that class of machines or devices which are controlled by keys or their equivalent, such as, for example, a computing machine or the like in which movable keys control the setting up mechanisms which in their turn control the operation of the printing or recording and computing mechanisms or either of them. In such machines the printing and computing mechanisms are generally actuated by the operation of a hand lever or equivalent means which is either given a partial or entire rotation or other movement for each operation of said mechanism. The device is applicable to any machine or construction however, wherein one or more movable keys are employed and it is desired or required to have an intermittent movement of a certain part of the mechanism or machine.

My invention pertains particularly to a construction in which the operating mechanism is controlled by the operation of the controlling keys of the machine. In the machine shown in the drawings, only a portion of the computing machine being shown, the setting up mechanism is controlled by an initial movement of the keys, the operating mechanism being controlled by an additional or secondary movement of the same keys.

To this end my invention consists in the novel construction, arrangement, and combination of parts herein shown and described and more particularly pointed out in the claims.

In the drawings, wherein like reference characters indicate like or corresponding parts, Figure 1 is a side elevation of a portion of any suitable form of computing machine or the like embodying my invention, (one row of keys shown), Fig. 2 is a top elevation of the same, Fig. 3 is a side elevation similar to Fig. 1 showing the parts in different positions, Fig. 4 is a sectional view of the preferred form of clutch mechanism taken substantially on line 4—4 of Fig.

5, Fig. 5 is a sectional view of the same taken substantially on line 5—5 of Fig. 4, 55 Fig. 6 is a perspective view of a detail of the operating mechanism, Fig. 7 is a side elevation of one of the preferred movable keys, Fig. 8 is a sectional view of the same taken substantially on line 8—8 of Fig. 7, 60 and Fig. 9 is a perspective view of a detailed part of the clutch mechanism.

Referring to the drawings a computing machine is shown in part; it being considered sufficient for a description and illustration to show only a part of the machine, the setting up mechanism, printing or recording mechanism and computing mechanism which may be of any suitable form, arrangement or combination of parts not being 70 shown in detail.

1 is a part of the frame or casing of the machine which is preferably arranged to print the items and compute the same or either print or compute the same. The setting up mechanism of the machine (not shown) is controlled preferably by a plurality of movable keys 3—3, etc. There may be any number of keys and they may be arranged in any suitable way or be of any 80 preferred design. After an item is set up, in the machine shown, by the operation of the keys and setting up mechanism controlled by the keys or a computation made or total taken, the operating shaft 4 is given a partial rotation causing the machine to perform the desired function. In the preferred construction shown driving means are provided to operate shaft 4 as desired, the construction comprising an arrangement where- 90 by the driving means and operating shaft 4 are normally disconnected or out of engagement and the driving of the operating shaft 4 controlled by any one of the movable keys 3—3, etc., or the key 2. There is a section 95 of keys 3—3, etc., for each numerical order within the capacity of the machine, the same being so arranged that after an item is set up by the setting up mechanism through the operation of the required keys, 100 by a further operation of a particular key, or of any one of the keys if the machine is so arranged, the movement of the driving shaft 5 will be transmitted to the operating shaft 4 thereby causing the machine to per- 105 form its functions in the desired manner.

In the same manner in the machine shown the shaft 4 is operated when the key 2 controlling the totaling mechanisms is operated.

Referring particularly to Fig. 8 in which the preferred form of key is shown, the key part 3 is provided with a shank or stem 6, which coöperates with the other part or member 7, as shown telescoping therewith. A resilient member 8, or the equivalent, is arranged substantially between the two as shown. To operate or control the setting up mechanism the key is depressed, the resiliency of the member 8 being such that the part 7 is depressed with the part 6 (see Fig. 1 and dotted position in Fig. 3) thus controlling the setting up mechanism (not shown) suitably connected therewith and controlled thereby. This may be termed an initial movement and controls the setting up mechanism as mentioned, so that these keys may be termed the controlling keys for the machine. If the key is pushed still farther (see Fig. 3) the part 7 having reached the limit of its travel as shown in Fig. 1 and 25 operated or controlled the setting up mechanism, the key parts 6 and 7 will telescope, contracting the resilient member 8 thus permitting a further or secondary depression of the key. Any equivalent arrangement may 30 be employed to accomplish the same result. Any suitable means may be employed to prevent the parts 6 and 7 of the key shown from separating, a simple arrangement being a pin 9 through the stem 6 coöperating 35 with a slot 10 in part 7 permitting the required movement of the two relative to each other but preventing separation.

In the preferred construction the driving mechanism or member comprises a continuously rotating or driving shaft 5, or the equivalent, which is operatively connected by suitable means, including clutch mechanism, or the equivalent, which is controlled by the secondary movement mentioned of 45 any of the keys. The preferred clutch mechanism shown comprises parts 12 and 13 loosely arranged or supported on a suitable pin or shaft 14. Clutch part 12 is provided with the usual form of gear teeth, 50 which mesh with the gear 11 secured to the driving shaft 5, which shaft may be driven by a motor (not shown) or any equivalent source of power so that the part is driven and continuously rotates with the shaft. 55 The part 13 of the clutch is connected by means of a bar 15 or the equivalent to a crank arm 17 secured to the shaft 4, the bar 15 being pivotally secured at points 16 and 18 to the clutch part and to the arms 17 60 respectively. The arm 17 is rigidly secured to the shaft 4 by means of a pin 19 or its equivalent. To substantially connect parts 12 and 13 of the clutch to operate the shaft 4 as desired, a pawl 20 or its equivalent is 65 provided and eccentrically mounted upon

member 13 in a recess 21, the pawl 20 being provided with a friction face 22 adapted to engage the face 23 on part 12. A resilient member 24 or its equivalent tends normally to force the pawl into engagement with the face 23 of part 12. As shown the pawl is preferably extended as at 25 to engage a suitable stop or detent 28. When the detent engages the pawl the parts of the clutch are thrown out of engagement and part 13 held at rest. The pawl may be secured to part 13 if desired, by means of a pin 26 or the equivalent for the purpose passing through the pawl and a tongue 27 on part 13. The stop or detent for the pawl 28 is preferably provided with an arm 30 rigidly secured to arm 28 so that the two form substantially a bell crank. Normally the stop or detent 28 is in the position shown in Fig. 1, Fig. 3 showing its position when the pawl is released to permit or cause the operation of shaft 4. This form of clutch mechanism and stop is particularly adapted for use in machines of the kind mentioned, as the stop not only operates the clutch mechanism, but also substantially locks the parts or prevents rotation of the driven member and operating shaft 4 when the pawl releases the part 13.

To operate or withdraw the stop 28 as required or desired, thereby releasing the pawl, I preferably provide an auxiliary arm or bar 31 carried by the arms 32 and 33, the bar being preferably pivotally secured thereto at points 34 and 35 respectively. The arm 32 is rigidly secured to a shaft 36, and provided with a bell crank arm 37, and the arm 33 is pivotally secured at 38 and provided with an arm 39, the two forming substantially a bell crank 38-39. The arms 37-39 are preferably connected by a bar 40 pivotally secured thereto at points 41 and 42 respectively. An arm 43 corresponding to arm 37 is also preferably secured to shaft 36 on the opposite side of the machine and an arm 44 corresponding to 39 pivotally secured to the frame (see Fig. 2), the two being connected by a bar 45 substantially similar to bar 40 and the arms 40 and 45 are connected by means of the connecting bar 46. On bar 31 (see Figs. 1 and 3) is provided a pin 53 or the equivalent which co-operating with arm 30 controls the stop 28 when bar 31 is moved in a manner herein-after described. A resilient member 54 secured to the frame at 55 and to the detent or stop 28 tends to normally hold or draw the stop into normal or operative stopping position, the parts being retained in this position by means of a stop 56 on the frame 125 working through the arm 32, bar 31, pin 53 and arm 30. Any other equivalent arrangement to accomplish the desired result may be employed. The shaft 36 is also provided with a plurality of arms 47 (see Fig. 2) se- 130

cured thereto, and a plurality of arms 48 arranged along the side of or proximate to the keys, the same being pivotally secured to the arms 47 at 49 and resting in depressions or recesses 50 (see Fig. 6) in the connecting bar 46, a plate 51 or the equivalent preventing the bars 48 from dropping down or through. Each key is provided with what may be termed a lug or extension 52 arranged to coöperate with the adjacent bar 48, etc. when the key is pushed into its secondary position (see Fig. 3).
 The operation of the device is substantially as follows: Assuming shaft 5 to be continuously rotated or driven in the direction so as to rotate the part 12 of the clutch in the direction indicated by the arrow in Fig. 1, and also assuming that it is not desired to operate shaft 4 until several keys have been depressed and the setting up mechanism controlled, so that the detent 28 is in the position shown in Fig. 1, the operating mechanism of the machine will be normally at rest or out of engagement with the driving mechanism. It is sufficient to describe the movement of the last key depressed in order to make clear the operation of the machine. Assuming therefore that the third key from the bottom in the right hand column is initially depressed as shown in Fig. 1 thereby controlling the setting up mechanism. This being the last key operated if it is desired to print or record the item the key is depressed still further or to its secondary position as shown in Fig. 3. This forces down the adjacent bar 48 and consequently depresses the arms 47 and bar 46 partially rotating shaft 36 and moving the arms 32 and 33, consequently throwing bar 31 so that the pin 53 moves the bell crank 28—30 whereby the detent or stop 28 releases the pawl 21. The resilient member 24 and driving force of the part 12 force the pawl into driving engagement with the part 12 so that the part 13 is frictionally driven by the part 12, until the same makes a complete rotation and the pawl is again engaged by the detent or stop 28. This movement gives shaft 4 a partial rotation thus operating the printing or recording mechanism of the machine shown. The operation and result is the same when key 2 which is similar to keys 3, controlling the totaling or computing is depressed. It should be noted that in the preferred construction and in the machine shown the operation of shaft 4 releases the key or keys and permits them to return to an inoperative position thereby permitting the detent 28 to return to its operative stopping position.
 The bar 40 is shown provided with a thumb or finger plate 57 (see Fig. 2) it being readily understood that the driving mechanism and operating shaft may be operated by depressing the bar 46, bar 40 or

45. Although the mechanism is shown as controlled by any or all of the keys it may be so arranged that it will be controlled by the operation of only one of them or a portion of them. 70

While the device is shown as applied to a computing machine of the kind described it is obvious and should be distinctly understood that the construction shown or modified construction embodying the invention may be employed wherever applicable and in any machine using one or more movable keys or the equivalent, the keys being longitudinally, pivotally or otherwise movable, where it is desired to transmit an intermittent movement to an operating or other part, and that it is applicable to any type of machine arranged to compute and print or record or to do either operation separately, etc. 75

Having thus described my invention it is obvious that various immaterial modifications may be made in the arrangement, construction and combination of parts shown and described, without departing from the spirit of my invention, hence I do not wish to be understood as limiting myself to the exact construction, arrangement and combination of parts or uses, shown, described or mentioned. 80

What I claim as new and desire to secure by Letters Patent is:

1. A device of the kind described comprising a group of controlling keys divided into series to correspond with the different numerical orders, said keys being formed in sections whereby they have a primary and a secondary movement, operating mechanism normally at rest, a detent for said operating mechanism, and means coöperating with one of said keys upon the secondary movement thereof to remove the detent from the operating mechanism said means being normally out of operative engagement with the keys. 90

2. In a device of the kind described and in combination, a group of controlling keys divided into series to correspond with the different numerical orders, said keys being formed in movably connected sections, whereby they have a primary and a secondary movement, operating mechanism normally at rest, a detent for said operating mechanism, and means normally out of operative engagement with the keys and coöperating with any of said controlling keys in the secondary movement thereof for removing the detent from the operating mechanism. 100

3. In a device of the kind described and in combination, a plurality of controlling keys having yieldably connected sections whereby to produce a primary setting up movement and a secondary movement, an operating shaft, a driven shaft normally disconnected 105

110

115

120

125

130

therefrom, and means connecting said shafts coöperating with any of said keys in the secondary movement thereof.

4. In a device of the kind described and in combination, operating mechanism and a series of controlling keys therefor, driving mechanism for said operating mechanism normally out of engagement therewith and means coöperating with one or more of said controlling keys for throwing said driving and operating mechanisms into engagement, said means including clutch mechanism comprising a rotatable driving member, a driven member rotatable concentrically therewith, and a pawl arranged to operatively connect said members, a movable stop arranged to be maintained in the path of said pawl, means for operatively connecting said stop and one or more of said keys, and means for operatively connecting said driven member and said operating mechanism.

5. In a device of the kind described and in combination, operating mechanism, a series of controlling keys, driving mechanism for said operating mechanism normally out of engagement therewith, and means coöperating with one or more of said controlling keys for throwing said driving and operating mechanisms into engagement, said means including a friction clutch comprising a rotatable driving member provided with an annular concentric engaging surface, a driven member rotatable concentrically therewith, and an engaging member pivotally supported at one end by said driven member and eccentrically disposed thereon, said engaging member arranged to engage said engaging face but projecting beyond the same, and a removable stop for said engaging member controlled by one or more of said keys and normally arranged in the path of the projected end of said engaging member in opposition to its line of travel and means for operatively connecting said driven member with the operating mechanism.

6. In a computing machine or the like, and in combination, a series of controlling keys, operating mechanism, driving mechanism therefor normally out of engagement therewith, and means for throwing said driving and operating mechanisms into engagement, said means including a friction clutch comprising a rotatable driving member provided with an annular concentric engaging surface, a driven member rotatable concentrically therewith, and an engaging member pivotally supported at one end thereof by said driven member and eccentrically disposed thereon, said engaging member arranged to normally engage said engaging surface but projecting beyond the same, a removable stop for said engaging member normally arranged in the path of the projected end of said engaging mem-

ber in opposition to its line of travel, and means operatively connected with said keys for operatively connecting said driven member with the operating mechanism.

7. In a computing machine or the like, and in combination, a series of controlling keys, operating mechanism, driving mechanism therefor normally out of engagement therewith, and means for throwing said driving and operating mechanisms into engagement, said means including a friction clutch comprising a rotatable driving member provided with an annular concentric engaging surface, a driven member rotatable concentrically therewith, and an engaging member pivotally supported at one end thereof by said driven member and eccentrically disposed thereon, said engaging member arranged to normally engage said engaging surface, but projecting beyond the same, and a removable stop for said engaging member normally arranged in the path of the projected end of said engaging member in opposition to its line of travel, controlling means governed by the movement of the keys for said stop, and means for operatively connecting said driven member with the operating mechanism.

8. In a computing machine or the like of the kind described and in combination a series of controlling keys, operating mechanism, driving mechanism therefor, and means arranged therebetween for operatively connecting the same, said means including a clutch comprising a rotatable driving part, a driven part and an engaging member arranged to operatively connect said parts, controlling means for said engaging member operatively connected with the keys and arranged to prevent rotation of said driven part when the parts are out of engagement, and means for operatively connecting said driving and operating mechanisms.

9. In a computing machine or the like of the kind described and in combination a series of controlling keys, operating mechanism and driving means therefor normally out of engagement therewith, said means including a clutch comprising a driving part and a driven part, means for substantially throwing the parts into operative engagement, controlling means therefor arranged to prevent the rotation of said driven part when out of engagement with said driving part, and operative connection between the controlling means and keys, and means for operatively connecting said driven part and said operating mechanism.

10. In a computing machine or the like and in combination, a series of controlling keys, operating mechanism, driving mechanism therefor normally out of engagement therewith including a clutch comprising a

driving part and a driven part, said driven part operatively connected with said operating mechanism, means for substantially throwing said driving and driven parts into engagement or preventing the engagement thereof, said means comprising an engaging member carried by one of said parts arranged to engage the opposite part, means tending to force the same into engagement, 10 means for normally preventing the engagement of said parts and means governed by the movement of the keys for controlling said stop.

11. In a computing machine or the like 15 and in combination, a series of controlling keys, operating mechanism, driving mechanism therefor normally out of engagement therewith including a clutch comprising a driving part and a driven part, said driven part operatively connected with said operating mechanism, means for substantially throwing said driving and driven parts into engagement or preventing the engagement thereof, said means comprising an engaging member carried by one of said parts arranged to engage the opposite part, means tending to force the same into engagement, 20 means for normally preventing the engagement of said parts and locking said driven part in an inoperative position comprising a 25 detent for said engaging member arranged in the path thereof in opposition to its line of travel and means operatively associated with the keys for controlling said 30 detent.

12. In a machine of the character described, the combination of a plurality of controlling keys having an engaging part, an elongated longitudinally extending arm or bar adapted to be engaged by said part in its movement, an auxiliary elongated longitudinally extending arm or bar, a bell crank lever operatively connected at opposite ends to said arms and pivotally supported intermediate its ends whereby a movement of one arm imparts a movement to the other, operating mechanism, a driven member, a drive interposed between the two, and means governed by the movement of the auxiliary arm to operate the drive.

13. In a machine of the character described, the combination of a plurality of controlling keys, an elongated longitudinally extending arm or bar adapted to be engaged by said keys in their movement, an auxiliary elongated longitudinally extending arm or bar, a bell crank lever operatively connected at opposite ends to said arms and pivotally supported intermediate its ends whereby a vertical movement of one arm imparts a longitudinal movement to the other, operating mechanism, a driven member, a clutch interposed between the two, and means governed by the movement of the auxiliary arm to operate the clutch.

14. In a machine of the character described, the combination of a plurality of controlling keys having an engaging part, an elongated longitudinally extending arm or bar adapted to be engaged by said part in its movement, an auxiliary elongated longitudinally extending arm or bar adapted to be engaged by said part in its movement, a bell crank lever operatively connected at opposite ends to said arms and pivotally supported intermediate its ends whereby a movement of one arm imparts a movement to the other, operating mechanism, a driven member, a releasable connecting means interposed between the two, and means governed by the movement of the auxiliary arm to operate the clutch comprising a bell crank lever operatively connected with the auxiliary arm and clutch respectively.

15. In a machine of the character described, the combination of a plurality of controlling keys, having an initial setting up movement and a secondary movement, said keys also having an engaging part, an elongated longitudinally extending arm or bar adapted to be engaged by said part in secondary movement of the keys, an auxiliary elongated longitudinally extending arm or bar, a bell crank lever operatively connected at opposite ends to said arms and pivotally supported intermediate its ends whereby a movement of one imparts a movement to the other, operating mechanism, a driven member, a releasable clutch connection between the operating mechanism and driven members, and means operatively connected with the auxiliary arm to release the clutch connection between the operating mechanism and driven member.

16. In a machine of the character described, the combination of a plurality of controlling keys having an engaging part, an elongated longitudinally extending arm or bar adapted to be engaged by said part in its movement, an auxiliary elongated longitudinally extending arm or bar, a pivotal connection between said arms whereby a movement of one imparts a movement to the other, operating mechanism, a driven member, a releasable clutch connection between the operating mechanism and driven members, and means operatively connected with the auxiliary arm to release the clutch connection between the operating mechanism and driven member, the said clutch acting automatically to couple the operating mechanism and driven member only after the keys have moved a predetermined distance.

17. In a machine of the character described, the combination of a plurality of controlling keys, an elongated longitudinally extending arm or bar, a lever operatively connected with the keys to actuate said arm, operating mechanism, a driven member, a clutch interposed between the operating

mechanism and driven member comprising coöperating members with means for maintaining them in relative locking connection, and means operatively connected with the elongated arm to release the clutch members.

18. In a machine of the character described, the combination of a plurality of controlling keys having an engaging part, an elongated longitudinally extending arm or bar adapted to be engaged by said part in its movement, an auxiliary elongated longitudinally extending arm or bar, a bell crank lever operatively connected at opposite ends to said arms and pivotally supported intermediate its ends whereby a movement of one imparts a movement to the other, operating mechanism, a driven member, a clutch interposed between the operating mechanism and driven member comprising coöperating members with means for maintaining them in relative locking connection, and means governed by the normal position of the auxiliary arm for maintaining said clutch members separated, said last mentioned means being moved by the auxiliary arm to operatively connect the clutch members.

19. In a machine of the character described, the combination of a plurality of controlling keys having an engaging part, an elongated longitudinally extending arm or bar adapted to be engaged by said part in its movement, an auxiliary elongated longitudinally extending arm or bar, a bell crank lever operatively connected at opposite ends to said arms and pivotally supported intermediate its ends whereby a movement of one imparts a movement to the other, operating mechanism, a driven member, a clutch interposed between the operating mechanism and driven member comprising coöperating members with means for maintaining them in relative locking connection, and means operatively connected with the auxiliary arm to release the clutch members only after the keys have moved a predetermined distance.

20. In a machine of the character described, the combination of a plurality of controlling keys having an engaging part, an elongated longitudinally extending arm or bar adapted to be engaged by said part in its movement, an auxiliary elongated longitudinally extending arm or bar, a bell crank lever operatively connected at opposite ends to said arm and pivotally supported intermediate its ends whereby a movement of one imparts a movement to the other, operating mechanism, a driven member, a clutch interposed between the operating mechanism and driven member comprising concentrically arranged rotary members one of which being operatively connected with the operating mechanism and the other with the driven member, a releasable locking dog interposed between the clutch members,

and means operatively connected with the auxiliary arm and to engage said dog and release the clutch members.

21. In a machine of the character described, the combination of a plurality of controlling keys having an engaging part, an elongated longitudinally extending arm or bar adapted to be engaged by said part in its movements, an auxiliary elongated longitudinally extending arm or bar, a bell crank lever operatively connected at opposite ends to said arms and pivotally supported intermediate its ends whereby a movement of one imparts a movement to the other, operating mechanism, a driven member, a clutch interposed between the operating mechanism and driven member comprising concentrically arranged rotary members, one of which being operatively connected with the operating mechanism and the other with the driven member, a releasable locking dog interposed between the clutch members, means operatively connected with the auxiliary arms to engage said dog and release the clutch members and hold them released during the normal position of the auxiliary arm, the said dog being adapted to automatically operatively connect the clutch members in the movement of said auxiliary arm due to the action of said keys.

22. In a machine of the character described, the combination of a plurality of controlling keys having an engaging part, an elongated longitudinally extending arm or bar adapted to be engaged by said part in its movements, an auxiliary elongated longitudinally extending arm or bar, a bell crank lever operatively connected at opposite ends to said arms and pivotally supported intermediate its ends whereby a movement of one imparts a movement to the other, operating mechanism, a driven member, a clutch interposed between the operating mechanism and driven member comprising concentrically arranged rotary members, one of which being operatively connected with the operating mechanism and the other with the driven member, a releasable locking dog interposed between the clutch members, means operatively connected with the auxiliary arm to engage said dog and release the clutch members and hold them released during the normal position of the auxiliary arm, the said dog being adapted to automatically operatively connect the clutch members in the movement of said auxiliary arm due to the action of said keys, said keys and said mechanisms being constructed and arranged whereby the keys may operate to control the setting-up mechanism without disturbing the normal position of said auxiliary arm.

23. In a machine of the character described, the combination of a group of controlling keys divided into series to corre-

spond with the different numerical orders, operating mechanism, a driven member, a clutch interposed between the operating mechanism and driven member comprising 5 coöperating rotary members, a locking part interposed between said clutch members, means for normally holding said locking part out of operative position, and means governed by the movement of the keys to 10 permit the locking part to move to a locking position.

24. In a machine of the character described, the combination of a group of controlling keys divided into series to correspond 15 with the different numerical orders, operating mechanism, a driven member, a clutch interposed between the operating

mechanism and driven member comprising coöperating rotary members, a locking dog interposed between the coöperating clutch 20 members, a crank arm connected to the driven member, an arm pivoted at one end to the crank arm and having an eccentric connection at its opposite end with one of said clutch members, and means governed 25 by the movement of the keys to control said locking dog.

In testimony whereof, I have hereunto signed my name in the presence of two subscribing witnesses.

DANIEL W. SHIEK.
